UNITED STATES PATENT OFFICE.

LAWRENCE M. RHOADES, OF KANSAS CITY, MISSOURI, ASSIGNOR OF ONE-HALF TO WALTER M. TETER, OF SAME PLACE.

DESIGN FOR AN ARTIFICIAL-THUMB-NAIL CORD-CUTTER.

SPECIFICATION forming part of Design No. 31,130, dated July 4, 1899.

Application filed May 27, 1899. Serial No. 718,586. Term of patent 14 years.

To all whom it may concern:

Be it known that I, LAWRENCE M. RHOADES, of Kansas City, Jackson county, Missouri, have invented and produced a new and useful Design for Artificial-Thumb-Nail Cord-Cutters, of which the following is a full, clear, and exact description, reference being had to the accompanying drawings, forming a part thereof.

10 My invention relates to a new and useful design for artificial-thumb-nail cord-cutters. In the drawings, Figure 1 is a perspective view. Fig. 2 is a vertical longitudinal section, and Fig. 3 is a cross-section of a cord-cutter, showing my new design, and the leading or material feature of the same resides in the substantially thumb-nail shape of the body portion and the curved arms projecting from said body portion, said body portion and arms (when viewed from front or rear) extending circularly—that is, forming a curve which if sufficiently extended would form a circle.

Minor features of my design reside in the downwardly-curved and tapering front end 25 and the upwardly-curved and flaring rear end of the body portion of the cord-cutter and in the rounded ends of the said arms.

Referring to the drawings in detail, 1 designates the substantially thumb-nail shaped 30 body portion of the cord-cutter, and 2 the curved arms thereof, the latter being rounded at their free ends, as at 3.

4 designates the downwardly-curved and tapering front end of the body portion, and 5 35 its upwardly-curved or flared rear end.

What I claim is—

The design for an artificial-thumb-nail cord-cutter, substantially as herein described and shown. 40

In testimony whereof I affix my signature in the presence of two witnesses.

LAWRENCE M. RHOADES.

Witnesses:

M. R. REMLEY,
A. J. WILLIAMSON.
